UNITED STATES PATENT OFFICE.

IRA SHAFFER, OF GRANT, IOWA.

ROTARY STEAM-ENGINE.

SPECIFICATION forming part of Letters Patent No. 666,981, dated January 29, 1901.

Application filed July 5, 1900. Serial No. 22,555. (No model.)

To all whom it may concern:

Be it known that I, IRA SHAFFER, a citizen of the United States, residing at Grant, in the county of Montgomery and State of Iowa, have 5 invented certain new and useful Improvements in Rotary Steam-Engines; and I do declare the following to be a full, clear, and exact description of the invention, such as will enable others skilled in the art to which it 10 appertains to make and use the same.

My invention relates to improvements in rotary steam-engines; and it consists in certain novel features of construction, combination, and arrangement of parts, as will be herein- 15 after more fully described, and particularly pointed out in the appended claims.

The object of the invention is to provide a rotary engine which may be readily reversed, which utilizes the expansive force as well as 20 the impact of the steam, and which is simple in construction, effective in operation, and embodies a minimum number of parts.

The invention is illustrated in the accompanying drawings, in which—

25 Figure 1 is an elevational view looking toward one side of the engine. Fig. 2 is a similar view looking toward the opposite side. Fig. 3 is a vertical section on line 3 3 of Fig. 1. Fig. 4 is a horizontal section on line 4 4 of Fig. 1. Fig. 5 is a horizontal section on line 5 5 of Fig. 1. Fig. 6 is a side view of the piston. Fig. 7 is an inner elevational view of one of the cylinder-heads, and Fig. 8 is a detail view of one of the piston-valves.

35 Referring now more particularly to the drawings, in which like reference-letters designate corresponding parts throughout the several views, A represents the engine-cylinder, comprising the base B, a central rim C, 40 two internal heads D and D', applied to the opposite sides of said rim and forming there- with the piston-chamber, and two outer plates or heads E and E', closing the steam-passages in said internal heads, as will be described 45 more fully hereinafter. The lower ends of these parts are elongated and form the base B, on which the cylinder rests.

50 F is the steam chest or space, located at the top of the cylinder and to which the steam- supply pipe F' is connected and provided with a valve of any approved type to control the passage of steam to the cylinder.

The piston G comprises a wheel or disk and is mounted in the cylinder upon a drive-shaft G', extending through the heads D D' and E E'. This piston is provided in each of its sides with a series of three or more tangential valve-chambers g, arranged equidistant from each other and concentric with the shaft. In these chambers are pivoted to move at right 60 angles to the plane of rotation of the piston a series of valves g', one in each chamber, each valve being of approximately L form, having a body portion g², pivotally mounted in the valve-chamber, and a lateral arm or 65 abutment g⁴, movable toward and from the chamber in an arcuate path at right angles to the axis of the piston. A spring g³ has one end fixed in the wall of the valve-chamber and its opposite end connected to the valve 70 and serves to project the valve or force it out from said chamber. The two series of valves on opposite sides of the piston face in reverse directions, and the faces of the arms or abutments g⁴ are beveled to ride easily on 75 the cylinder-heads and provide a balanced valve under perfect control of its spring- hinge.

The cylinder-heads D and D' are provided with segmental slots H and H', which are counterparts in form and construction, but are reversed in arrangement, being located on opposite sides of the vertical centers of said heads. The upper ends of these slots, which form passages for the circulation of the steam 80 through the cylinder, are in communication with the steam-chest F, while the lower ends thereof are in communication with exhaust- ports I, located in the heads D D' and E E'. The inner faces of the heads D D' are beveled 85 or inclined at the upper and lower ends of the slots, as shown at j j', the beveled surfaces j allowing the valves to gradually open as they enter the slots H H', while the beveled surfaces j' effect the closing of the valves 90 as they leave the slots. Spring-pressed pack- ing-strips K are arranged between the rim of the piston and rim of the cylinder and be- 95 tween the sides of the piston and heads D D' and form steam-tight closures to prevent the steam from passing through the cylinder otherwise than through the steam-passages H H'. The valves g' are so arranged that at 100 least one valve at a time occupies each pas-

sage $H H'$, so that a continuous motion of the piston is insured and loss of live steam prevented. The upper and lower ends of each of the passages $H H'$ are in communication 5 through the medium of suction or relief passages l , which are adapted to allow the steam to follow the series of valves on either side when that side is working backward, and thus prevent suction and back pressure.

- 10 The reversing mechanism is arranged in duplicate, one set on each side of the cylinder, and each set consists of a vertically-reciprocating valve-rod m , connected at its upper end by a link or crank-arm o with a rod or 15 shaft m' , extending through the steam-chest, to which rod is also connected a reverse-lever n , provided with a pawl p to engage a segment-rack p' , mounted on the steam-chest. At its lower end the valve-rod is operatively 20 connected with two valves q and q' , which respectively control the exhaust-port I and relief or suction port or passage l . The valve q' is pivoted to move in the arc of a circle upon the outer side of the cylinder, so as to 25 cover and uncover the exhaust-port I , while the valve q is an ordinary rotary plug-valve mounted in the side of the cylinder, so as to extend across and open and close the relief- 30 passage l . These valves are arranged and mounted to operate alternately, so that when the valve q' covers and closes the exhaust-port I the valve q will be turned to the proper position to open the relief-port l , and vice versa. The two links or crank-arms o are 35 so mounted on the rod or shaft m' that the valve-rods m will be moved in reverse directions when the lever n is operated, so that when the plug-valve q of one set is turned to close its relief-port l the corresponding valve 40 q of the other set will be turned to open the other relief-passage controlled thereby, while the valves q' will be swung in reverse direction to cover and uncover their exhaust-ports I in like manner. By this means the valves 45 may be simultaneously operated to open the exhaust-port and close the relief-port on the working side of the engine and to, on the contrary, open the relief-port and close the exhaust-port on the opposite or idle side of 50 the engine.

It will be observed that the relief-valve q' is an ordinary rotary valve mounted in the head D and plate E and crossing the lower portion of the passage l , whereas the valve q 55 swings in the arc of a circle toward and from the port I to cover and uncover the same. As the valve q is moved toward the port I to close it the valve q' is turned to bring the port or opening therein in line with the passage l to 60 open the same, and, on the other hand, when the valve q is moved away to uncover the port I the valve q' is turned in the reverse direction to close the port l .

In the practical operation of the engine 65 steam may be admitted to either side of the piston to work freely, and thus cause the pis-

ton to rotate in either direction. If it be desired, for instance, to cause the steam to act on the piston-valves coacting with the steam-passage H on one side of the cylinder to operate the piston in one direction, the valve mechanism on that side is moved to open the exhaust-port and close the relief-port, while the valve mechanism on the opposite side is moved to cause the valve q to close the exhaust-port I at the lower end of the steam-passage H' and the valve q' to open the relief-passage l . The throttle-valve is then opened and steam admitted into the cylinder, and as the exhaust-port of the passage H' is closed 75 and the exhaust-port of the passage H is open the steam will take the latter course—the course of free discharge and of least resistance—and will circulate through the passage H , acting on the piston-valves coöperating 80 therewith and rotating the piston. The valves on each side are three in number and arranged equidistantly, so that at least one valve always occupies the passage H or H' , and accordingly a smooth and continuous rotation of the piston is effected, and both the impact and the expansive force of the steam are utilized. As each valve q in the rotation 85 of the piston approaches the inlet end of the passage H the arm or abutment g^4 thereof rides upon the beveled surface j and the spring g^3 forces the valve open, so that it closes the passage H and receives the full impact and expansive force of the steam. When the valve reaches the outlet end of the 90 said passage H , it is forced closed by the beveled face j' , and the steam following behind the valve discharges through the exhaust-port I at the same time that the next succeeding valve enters the steam-passage. Steam 95 is simultaneously admitted to both sides of the piston to maintain a parity of pressure on each side; but the steam operates on the valves on that side of the piston having the exhaust-port open and providing for the free 100 discharge of the steam. The purpose of the relief or suction port l is to allow the steam to follow the valves on the side working backward or which is not in use, thereby preventing suction and back pressure. The operation 105 of reversing the engine to bring the side containing the steam-passage H' into active 110 operation will be readily understood from the foregoing description.

It will be seen that the invention provides 115 an engine of the rotary type which is readily reversible, which obviates side and back pressure and utilizes the impact and expansive force of the steam, and which is simple in construction and embodies comparatively few 120 parts. The construction and arrangement of the piston valves or abutments also provide for a perfect sensitive balancing of the valves and the easy and effective operation thereof.

Changes in the form, proportion, and minor 125 details of construction may be made within 130

the scope of the invention without departing from the spirit or sacrificing any of the advantages thereof.

Having thus fully described my invention, 5 what I claim as new and useful, and desire to secure by Letters Patent of the United States, is—

1. In a reversible rotary steam-engine, the combination of a cylinder provided with reverse counterpart steam-passages in communication at their induction ends with a source of steam-supply and at their eduction ends with exhaust-ports, relief ports or passages connecting the said induction and eduction 15 ends of each passage, a piston carrying two sets of reverse valves or abutments coöperating with said steam-passages, and valve mechanism coöperating with each set of relief and exhaust ports and adapted to alternately open and close the same, substantially as set forth.

2. In a reversible rotary steam-engine, the combination of a cylinder provided with reverse counterpart steam-passages in communication at their induction ends with a source of steam-supply and at their eduction ends with exhaust-ports, relief ports or passages connecting the said induction and eduction 25 ends of each passage, a piston comprising a wheel or disk provided in its opposite sides with valve-chambers, valves of L form in said

chambers and facing in reverse directions, and springs adapted to project the valves, said valves being movable in arcs at right angles to the plane of rotation of the piston, 35 and valve mechanism coöperating with each of the relief and exhaust ports and adapted to alternately open and close the same, substantially as set forth.

3. In a reversible rotary steam-engine, the combination of a cylinder provided with reverse counterpart steam-passages in communication at their induction ends with a source of steam-supply and at their eduction ends with exhaust-ports, a piston carrying two sets 45 of reverse valves or abutments coöperating with said steam-passages, relief ports or passages connecting the said induction and eduction ends of each passage, and valve mechanism for controlling each set of ports, the 50 same comprising a reciprocating valve-rod, valves operated thereby to alternately open and close the ports, and an operating-lever connected to said rod, substantially as set forth.

In testimony whereof I have hereunto set my hand in presence of two subscribing witnesses.

IRA SHAFFER.
